PORTABLE DEGREASER

James J. Skelly, Cleveland Heights, Ohio, assignor
to Ciroc Products Company, Cleveland, Ohio,
a corporation of Ohio

Application May 7, 1945, Serial No. 592,386

6 Claims. (Cl. 219—38)

1

This invention relates to portable degreasers of the type embodying apparatus for injecting the vapor from a predetermined volume of solvent into the chamber containing the parts to be cleaned.

The invention further relates to improvements in degreasers of the type disclosed in Patents No. 2,259,544, 2,259,545, and 2,259,546, all issued October 21, 1941, to John F. Black, each of which contemplates a can supporting member having a heating element associated therewith and a coupling for the suspension of the assembly upon the article to be cleaned and the transmission of solvent vapors thereto.

The present invention comprehends the functions and advantages of the apparatus disclosed in the aforesaid patents and in addition pertains to mechanism for the control of the electric heating element; to mechanism for adjustment of the can supporting member relating to the plane of the work; to mechanism for safeguarding the use of the apparatus after disposition of the solvent vapor and to an apparatus which is efficient of operation, durable of structure and susceptible of use in more widely diversified environs than have heretofore been realized by degreasers of this character.

Other objects and advantages more or less ancillary to the foregoing and the manner in which all the various objects are realized will appear in the following description, which considered in connection with the accompanying drawings, sets forth the preferred embodiment of the invention.

Referring to the drawings wherein the preferred embodiment of the invention is illustrated:

Fig. 1 is a vertical section through the degreaser embodying the present invention;

Fig. 2 is a transverse section through the coupling member, the section being taken on a plane indicated by the line 2—2 in Fig. 1;

Fig. 3 is a schematic view of a fragmentary portion of an automobile rear axle illustrating the degreaser in place upon the differential housing thereof; and

Fig. 4 is a wiring diagram showing the electric circuit.

Referring first to Fig. 3, the degreaser for the differential gear case chosen herein as merely illustrative of one of the environs within which the improved apparatus may be used, comprises generally a frame member 10, a can or bottle 11 supported thereby and a conduit 12 adapted to support the frame and can assembly in self sustained suspension upon the differential gear case

13. The conduit is preferably attached to the case 13 by a threaded sleeve 14 mounted on the end of the conduit and secured in the filler or drain hole in the cover plate of the gear case. Removal of the grease-laden solvent condensate may be effected by extraction of the drain plug in the gear case or one of the bottom cover plate screws, when such screws communicate with the interior of the casing, or partial separation of the plate from the gear case or rear axle housing. 2

10 In detail the degreaser frame member 10 comprises a closed casing 16 having a tube 17 mounted in the outer end thereof upon which there is affixed a cup 18 internally threaded for the support of the can or bottle 11 containing the fluidic solvent employed in the degreasing operation. The lower portion of the tube 17 is provided with an electric heater 19 of the immersion type which, as illustrated, is formed with a resistance coil 20 wound about a hollow core 21 sealed at its lower end by a cup 22 and arranged in atmospheric communication with the interior of the tube 17 at the upper end thereof. Within the tube 17 there is a bulb 23 containing a thermal expansive material which is connected through a pipe 24 to a bellows 25 supported in a bracket 26 in the casing 16. The free end of the bellows is provided with a threaded thimble 27 having a nut 28 thereon for the support of the inner end of a spring 29. The opposed end of the spring is supported by a plate retained by the outer upturned end of the bracket 26. The thimble 27 supports a depending strap spring 30 constituting a switch arm disposed for engagement with a plunger 31 in an electrical snap action switch 32 suspended from the bracket 26. The switch arm projects through a slot in the base of the bracket and is retained in place upon the thimble 27 by the spring 29. The arm is formed of a material of sufficient rigidity to actuate the plunger but flexible when the distention of the bellows exceeds the throw of the switch. Longitudinal adjustment of the switch arm 30 relative to the plunger 31 may be effected by running the nut 28 inwardly or outwardly on the thimble 27. The opposed end portion of the plunger 31 is moved inwardly to circuit closing position by a spring blade 34 when actuated by a manually controlled button 35 guided in an apertured boss 36 in the casing 16. 30 The frame 10 is formed with a pistol grip handle 37 to accommodate manipulation of the assembly during attachment thereof upon the housing to be cleaned. The walls of the handle define a chamber of adequate size to house an incandescent light bulb 38 which is wired for illumination when

the switch 32 is adjusted to close the circuit to the electric heating coil 20. A lens 39 is mounted in the handle adjacent the light bulb to apprise the operator of the position of the switch 32.

The can holder or cup 18 is provided with a pipe 40 arranged in fluid communication with the interior of the can 11 and with the conduit 12 which conducts the solvent vapor to the work. The upper end of the pipe supports a tee 41 machined with gasket seats in the opposed side walls thereof and a series of notches 42 in the wall contiguous the portion of the conduit 12 that is attached to the work. The conduit 12 is provided with a fitting 43 affixed thereto and formed with lugs 44 configured for engagement within the notches 42 when the nut 45 is tightened upon the opposed threaded end portion of the conduit. The bore in the head of the tee is formed to provide a chamber circumambient the conduit 12 and the portion of the conduit within said chamber is cross drilled to afford fluid communication between the pipe 40 and the conduit. The body of the conduit is bent at an obtuse angle intermediate its ends to accommodate the suspension of the can in a substantially vertical position when the axis of the filler plug opening within which the conduit is anchored is inclined downwardly. In installations where the filler plug is normal to the medial axis of the can the nut 45 may be loosened, the conduit revolving through an angle of 90°, the lugs 44 reseated in the contiguous notches 42 and the nut then tightened to support the assembly in its adjusted position. In a like manner when the filler plug is inclined upwardly the conduit may be revolved 180° then locked against further rotation by reseating the lugs in the appropriate notches and tightening the nut 45. The free end of the conduit is threaded for the reception of the sleeve 14 which is externally threaded for engagement with the tapped filler plug hole in the casing to be cleaned. In using the degreaser on work of the same class it has been found that two or three sleeves having external threads of different size and pitch generally meet the demands. It is obvious, however, that an adapter may be used for such installations as preclude the use of a sleeve of the type illustrated herein.

In operation, after the lid is removed from the can of solvent the heating element is submerged in the fluid and the can screwed in place in the cup 18. The connecting plug or sleeve 14 is then inserted into the opening in the housing containing the grease laden parts and screwed down until a sufficient number of threads are engaged to support the frame and can assembly in self sustained suspension.

The switch button 35 is then pressed inwardly to a depth which will effect the translation of the plunger 31 to its circuit closing position. With the switch in this position the current will flow through the resistance coil 20 and the pilot lamp 38. As the coil becomes heated the core 21 and the heater cup 22 likewise become hot and the heat is transferred to the solvent circumambient the heater and to the air inside the core and tube 17. While the heater and tube are below the level of the solvent liquid, the temperature of the air within the tube 17 in contact with the thermal responsive bulb 23 remains below the boiling point of the solvent.

However, as the solvent is vaporized and the liquid level thereof falls below the upper surface of the heater 19, the heat transferred to the sol-

vent through the diminished contact area of the cup 22 therewith becomes less than the heat generated in the coil. The air within the heater and tube 17 undergoes a rapid temperature rise which in a relatively short time expands the material within the bulb 23, thereby actuating the switch mechanism, and opening the circuit to the heater coil 20 and the pilot lamp 38. After the flow of current to the heater is interrupted the remainder of the solvent in the container is vaporized by the residual heat in the heater unit. This is possible through consideration and arrangement of the following factors; the heat capacity of the heater, the heat of vaporization of the solvent, the depth of solvent in the can when the current is interrupted, and the position of the heater relative the bottom of the can.

It will be seen that irrespective of fluctuations in the operating voltage and of the initial temperature and/or height of solvent, the solvent will be completely utilized and the resistance coil will be free from the danger of overheating.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A degreaser comprising a can for a solvent, a frame for the support thereof, a conduit thereon adapted for fluid communication with the work to be cleaned and the interior of the can, an electric heater supported by said frame adapted for submersion in solvent in said can, an electric switch electrically connected with said heater, a push button on said frame for closing said switch, a distensible bellows thermostatic device having a thermal expansive material therein mounted on said frame in atmospheric communication with said heater and operative connections on said bellows for actuating said switch into circuit breaking relation with said heater upon distention of said bellows.
2. A degreaser comprising a container for a solvent, a frame for the support of the container, a conduit on the frame to support the degreaser in operative position upon the work and to conduct vaporized solvent to the work, a tube extending from the frame into the container, an electric heater of the immersial type mounted on the end of said tube, a bulb containing a thermally expansive material therein mounted in the said tube in spaced relation to said heater, a switch on said frame for controlling the supply of current to the heater, and means responsive to expansion of the material in the bulb for opening the switch.
3. A degreaser comprising a frame for the support of a can of solvent, a can thereon, fluid connections on said frame for the suspension thereof upon the work to be cleaned, a tube mounted on said frame, an electric resistance coil on the lower end of said tube, a bulb having a thermal expansive material therein mounted within said tube, a distensible bellows in fluid communication with said bulb, a switch electrically connected to said coil, a plunger in said switch, a push button on said frame engageable with one end of said plunger, an arm on said bellows engageable with the opposed end of said plunger, said plunger being arranged to close the electric circuit to said coil when actuated by said push button and to

break the circuit to the coil when actuated by said arm.

4. In combination, a container for a solvent and an electric heater, mechanism for breaking the circuit to the electric heater responsive to the dissipation of the solvent in said container under the influence of the heater, comprising a bulb having a thermal expansive material therein disposed in contiguous relation with the heater, a bellows in fluid communication with said bulb, a switch electrically connected with said heater, and an arm associated with said bellows for moving the switch into circuit breaking position when actuated by the distention of said bellows, the bulb being isolated from the solvent and being 15 affected by the heater through air convection.

5. A portable degreaser comprising a cup for the support of a container of solvent, a container thereon, an electric heater mounted on said cup, a switch electrically connected with said heater, a manual means for closing said switch, thermal responsive means for breaking the electric circuit through said switch, a conduit mounted in said cup, a coupling thereon, a second conduit bent intermediate its ends and attached to said coupling, means on the end of the bent conduit for the securement thereof to the work to be cleaned, and means in said coupling to lock the bent conduit in various positions of axial adjustment with respect to the first named conduit.

6. A portable degreaser comprising a can for a solvent, a cup for the support thereof, an electric heater mounted thereon, a switch electrically connected with said heater, manual means for closing said switch, thermal responsive means for breaking the electric circuit through said switch, a conduit mounted in said cup, a coupling thereon, a second conduit bent intermediate its ends and attached to said coupling, a screw plug on said bent conduit for engagement with the work to be cleaned, and interengaged lugs on said coupling disposed to lock the bent conduit against rotation when the end portion thereof is inclined either upwardly, downwardly or laterally.
